GARBAGE CONTAINER CART

James W. Land, 2112 Patou Drive, Jacksonville, Fla.

Filed May 20, 1963, Ser. No. 74,953

Term of patent 3½ years

(Cl. D14—3)

FIG. 1.

FIG. 2.

FIG. 3.

FIG. 4.

FIG. 1 is a left side elevational view of the garbage container cart embodying my new design with the broken line portions being included for illustrative purposes only; FIG. 2 is a front elevational view; FIG. 3 is a rear elevational view; and FIG. 4 is a top plan view.

I claim:

The ornamental design for a garbage container cart, substantially as shown.
